UNITED STATES PATENT OFFICE.

DELBERT COOLEY, OF GALENA, KANSAS.

GAS AND AIR BURNER.

No. 850,996.

Specification of Letters Patent.

Patented April 23, 1907.

Application filed November 2, 1905. Serial No. 285,545.

To all whom it may concern:

Be it known that I, DELBERT COOLEY, a citizen of the United States, and a resident of Galena, in the county of Cherokee and State of Kansas, have invented a new and Improved Gas and Air Burner, of which the following is a full, clear, and exact description.

The object of the invention is to provide a new and improved gas and air burner for use in heaters, furnaces, and the like arranged to cause a thorough mixing of the gas and air previous to ignition of the mixture with a view to insure a complete combustion of the mixture, the arrangement also permitting independent regulation of the supply of gas and air according to the richness of the gas.

The invention consists of novel features and parts and combinations of the same, which will be more fully described herein-after and then pointed out in the claims.

A practical embodiment of the invention is represented in the accompanying drawings, forming a part of this specification, in which similar characters of reference indicate corresponding parts in both views.

Figure 1 is a sectional side elevation of the improvement, and Fig. 2 is a perspective view of the gas-valve and the mixing-disk.

The mixing-tube A is adjustably secured in a bracket B by means of a set-screw C, the said bracket extending from the angular end D' of a gas-supply pipe D, connected at the terminal of the angular end D' by a pipe E with a suitable gas-supply. Within the gas-supply pipe D is arranged a nut D², in which screws the threaded portion F' of a rod F, extending through a suitable stuffing-box D³ to the outside of the gas-supply pipe D, and on the outer end of the said rod F is secured a handle F² for conveniently turning the rod with a view to screw the same lengthwise in the supply-pipe D.

On the inner end of the rod F is formed or secured a tubular gas-regulating valve F³, extending through the inner end D⁴ of the gas-supply pipe D, and the said tubular regulating-valve F³ is provided with apertures F⁴, arranged within the gas-supply pipe D, to allow the gas to pass from the same through the openings F⁴ into the gas-regulating valve F³. The outer portion of the gas-regulating valve F³ is provided with lengthwise-extending slots F⁵, through which the gas escapes from the inside of the valve F³ into the mixing-tube A, as plainly indi-

cated by the arrows in Fig. 1. On the outer end of the valve F³ is secured a mixing-disk G, extending transversely in the tube A and reaching to the inner wall thereof, the said disk having angularly-disposed vanes to form spaces between the edges of adjacent vanes for the passage of the gas and air to insure a complete mixture thereof.

The air-entrance end of the mixing-tube A is provided with a flaring mouth or flange A', opposite which is arranged a correspondingly-shaped disk H, held adjustable on the gas-supply pipe D by the use of a set-screw I. Thus by loosening the set-screw I and moving the disk H nearer or farther from the mouth A' it is possible to regulate the amount of air passing into the mixing-tube A. By adjusting the rod F lengthwise in the supply-pipe D, as previously described, an inward or outward sliding motion is given to the valve F³, so that the slots F⁵ extend more or less into the mixing-tube A, and consequently a minute regulation of the amount of gas passing into the mixing-tube A is had. Thus from the foregoing it will be seen that the amount of air and gas to be mixed within the tube A can be regulated independent one of the other, according to the richness of the gas, to insure the formation of a properly-combustible mixture of gas and air.

It is understood that the air passing through the mouth A' into the mixing-tube A comes in contact and mixes with the gas escaping through the slots F⁵, and this mixture of gas and air passes between the adjacent vanes of the disk G, so that a further intimate mixture of the gas and air takes place, to form a highly-combustible mixture to be burned at the outer end of the mixing-tube A.

The device is very simple and durable in construction and is composed of comparatively few parts not liable to get easily out of order.

Having thus described my invention, I claim as new and desire to secure by Letters Patent—

1. A gas and air burner, comprising a mixing-tube open at one end for the admission of air and open at the other end for the discharge of the combustible mixture of gas and air, a gas-supply pipe connected with a gas-supply and extending into the said mixing-tube, a tubular valve adjustable lengthwise in the inner end of the said gas-supply pipe, the said valve having gas-inlet openings with

in the gas-supply pipe and slots opening into the said mixing-tube, and a mixing-disk within the mixing-tube having angularly-disposed vanes for the passage of the gas and air to insure a complete mixture thereof.

5. 2. A gas and air burner, comprising a mixing-tube open at one end for the admission of air and open at the other end for the discharge of the combustible mixture of gas and 10 air, a gas-supply pipe connected with a gas-supply and extending into the said mixing-tube, a tubular valve adjustable lengthwise in the inner end of the said gas-supply pipe, the said valve having gas-inlet openings

within the gas-supply pipe and slots opening 15 into the said mixing-tube, a mixing-disk within the mixing-tube having angularly-disposed vanes for the passage of the gas and air to insure a complete mixture thereof, and a flanged adjustable disk opposite the flanged 20 air-entrance end of the said mixing-tube.

In testimony whereof I have signed my name to this specification in the presence of two subscribing witnesses.

DELBERT COOLEY.
